CLAIM

The ornamental design for an in-vehicle display device, as shown and described.

DESCRIPTION

FIG. 1 is a front perspective view of an in-vehicle display device;

FIG. 2 is a rear perspective view thereof;

FIG. 3 is a partially enlarged view of an area 3-3 in FIG. 1;

FIG. 4 is a front view thereof;

FIG. 5 is a rear view thereof;

FIG. 6 is a top view thereof;

FIG. 7 is a bottom view thereof;

FIG. 8 is a right side view thereof; and,

FIG. 9 is a left side view thereof.

The broken lines shown are included for the purpose of illustrating portions of the in-vehicle display device that form no part of the claim.

1 Claim, 9 Drawing Sheets
